UNITED STATES PATENT OFFICE.

BARBARA E. IKAS, OF NEWARK, NEW JERSEY.

HAIR-CURLING DEVICE.

Application filed September 27, 1922. Serial No. 590,876.

To all whom it may concern:

Be it known that I, BARBARA E. IKAS, a citizen of the United States, residing at Newark, in the county of Essex and State 5 of New Jersey, have invented certain new and useful Improvements in Hair-Curling Devices, of which the following is a specification.

This invention relates to an improved 10 hair curling device and seeks as one of its principal objects to provide a simple, inexpensive device particularly adapted for the curling of bobbed hair.

A further object of this invention is to 15 provide a simple hair curling device which will permit of the curling of the outer end portions of the hair.

A further object of this invention is to 20 provide an extremely simple hair curling device which may be readily manufactured, and which will prove durable and efficient in operation.

A further object is to provide a hair 25 curler including main and auxiliary clips one of which constitutes a form or mandril upon which the hair may be wound and the other a tension device adapted to engage the hair and impart the desired set or curl thereto.

30 A further object is to provide a hair curler the construction of which is such as to effectually grip the hair and thereby prevent accidental slippage or displacement of the device during the curling operation.

35 Further objects and advantages will be apparent during course of the following description and by referring to the accompanying drawings, wherein for the purpose of illustration is shown the preferred embodiment of the invention, the several parts 40 thereof being designated by like numerals in all of the views,

Figure 1 of the drawings is a perspective view showing the invention applied and also 45 showing the method of application of the main clip of the invention to the end portions of the hair.

Figure 2 is a perspective view of the complete invention showing in full lines the 50 main and supplementary clips of the invention separated, and showing in dotted lines the supplementary clip applied upon the main clip.

Figure 3 is a longitudinal section through 55 the center of the complete invention.

Referring to the drawings, the numeral 1

generally designates a main clip, and the numeral 2 generally designates a supplementary clip which in use is applied to the main clip.

The main clip 1 is made from a single, narrow, thin strip of resilient metal which forms a straight shank 3 one end portion of which is bent to form a loop 4 terminating in a hook 5 in the extremity of which is 60 a semicircular niche 6. The other end portion of the strip is bent back against the shank forming a loop 7 and a tongue 8, said tongue being curved towards the shank and made with a tapering rounded end 9 which 65 engages beneath the hook 5 at the niche 6 and holds the tongue securely against the shank 3. When the end 9 is disengaged from the hook 5 the resiliency of the clip tends to separate the tongue and shank and 70 permit the placing of hair between them. In the loops 4 and 7 are cut small slots 10 running longitudinally of the clip. These slots are narrow in order not to interfere with the resiliency of the clip and extend but 75 about half way around the loops.

The supplementary clip 2 is likewise made from a single, narrow, thin strip of resilient metal and is formed as a slightly curved or dished shank 11 having one end 80 portion bent into a loop and hook 12 and the other end portion cut much narrower than the shank 11 and bent into a small hook 13. In using the conventional types of clip curlers, the hair is wound about a 85 shank or former, beginning near the roots and finishing at the ends of the hair, after which the tongue is clipped over the roll of hair. It is a well known fact that the end portions of the hair, being last wound 90 on such a clip, easily slip off and are not curled. This invention aims to overcome this difficulty and provide a clip curler that will efficiently curl the end portions of hair, which curling is especially desirable for 95 bobbed hair. By referring to Figure 1 the application of this curler will be apparent.

The clip 1 is opened, hair 14 is placed between the tongue 8 and shank 3 and the clip is closed, the resiliency of the clip holding 100 the hair within it. The clip 1 is then drawn out until it engages only the extreme end portions of the hair and is then rotated, thereby winding the hair about both shank and tongue of the clip until the desired 110 length of hair is wound thereon. The clip 2 is then applied outside of the roll 15 of

2
hair by engaging the small hook 13 in either of the slots 10 in the loops 4 or 7 and engaging the hook 12 about the opposite loop, the inherent resiliency of the inwardly curved or dished portion of the shank holding said shank tightly against the hair.

Thus it will be seen that the end portions of the hair are in the center of the roll and cannot possibly slip out of the curler and are 10 curled all the more efficiently for being so positioned. It is of course to be understood that the illustration shows the preferred embodiment of the invention and that such slight changes may be made in the invention 15 as are within the spirit of the invention and the scope of the appended claims.

Having thus described the invention, what is claimed as new is:

1. A hair curler including a clip for attachment to a lock of hair to be rotated for rolling the hair about the clip and provided at one end with an opening, and a separate supplementary clip formed at one end with a hook to engage in said opening 25 and provided at its opposite end with means to engage the opposite end of said first-mentioned clip coacting with the roll of hair locking said first-mentioned clip against counter rotation.

2. A hair curler including a clip provided at its ends with loops, the loop at one end of said clip having an opening therein, and a supplementary clip to overlie said first-mentioned clip and provided at its ends with hooks one engageable in said opening and the other engageable over the loop at the opposite end of said first-mentioned clip. 30

3. A hair curler including a clip, and a separate independent supplementary clip 40 provided at its ends with hooks extending in the plane of the latter clip therebeneath to engage the terminals of the former clip coacting therewith.

4. A hair curler including a clip provided at its ends with loops each having an opening therein, and a separate independent supplementary clip to overlie said first-mentioned clip and provided at its ends with hooks one engageable in either of said 50 openings and the other engageable over either of said loops connecting the supplementary clip with said first mentioned clip, the supplementary clip being reversible end for end with respect to said first mentioned clip. 55

In testimony whereof I affix my signature.
BARBARA E. IKAS. [L. S.]
